Primary Examiner — Christy Nemeth*Assistant Examiner* — Sarah L Smith(74) *Attorney, Agent, or Firm* — Nitin Kaushik(57) **CLAIM**

The ornamental design for a flashlight, as shown and described.

DESCRIPTION

FIG. 1 is a perspective view of a flashlight showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is perspective view of the flashlight in an expanded state showing a charging port.

The broken lines in the drawings depict portions of the flashlights that form no part of the claimed design.

1 Claim, 7 Drawing Sheets(56)
